(72) Inventor: **David Phillip Winter**, Encinitas, CA
(US)

FOREIGN PATENT DOCUMENTS

(73) Assignee: **Covidien LP**, Mansfield, MA (US)

WO WO 2007/102866 9/2007

(***) Term: **14 Years**

OTHER PUBLICATIONS

(21) Appl. No.: **29/447,988**

U.S. Appl. No. 29/447,977, Notice of Allowance mailed Sep. 30, 2013, 2 pgs.

(22) Filed: **Mar. 8, 2013**

(Continued)

(51) **LOC (10) Cl.** **24-01***Primary Examiner* — Deanna L Pratt
Assistant Examiner — Lilyana Bekic(52) **U.S. Cl.****CLAIM**USPC **D24/107**

The ornamental design for an exhalation module EVQ housing, as shown and described.

(58) **Field of Classification Search****DESCRIPTION**USPC D24/107, 110, 110.6, 129, 127, 162,
D24/164, 108, 121; 600/529, 538, 543, 532
CPC A61B 5/08; A61B 5/4818; A61B 5/097;
A61B 5/091; A61B 5/087; A61M 16/10;
A61M 16/20

FIG. 1 is a perspective view of an exhalation module EVQ housing showing a new design.

See application file for complete search history.

(56) **References Cited**

FIG. 2 is a front view of an exhalation module EVQ housing showing a new design.

U.S. PATENT DOCUMENTS

FIG. 3 is a back view of an exhalation module EVQ housing showing a new design.

3,444,857 A	5/1969	Godel
3,481,333 A	12/1969	Garrison
3,485,243 A	12/1969	Bird et al.
3,688,794 A	9/1972	Bird et al.
4,241,756 A	12/1980	Bennett et al.

4,527,557 A	7/1985	DeVries et al.
4,608,976 A	9/1986	Suchy
4,699,137 A	10/1987	Schroeder
RE32,553 E	12/1987	Bennett et al.
4,712,580 A	12/1987	Gilman et al.
4,727,871 A	3/1988	Smargiassi et al.
4,747,403 A	5/1988	Gluck et al.
4,752,089 A	6/1988	Carter
4,880,411 A	11/1989	Fangrow et al.

FIG. 4 is a right side view of an exhalation module EVQ housing showing a new design.

FIG. 5 is a left side view of an exhalation module EVQ housing showing a new design.

FIG. 6 is a top view of an exhalation module EVQ housing showing a new design; and,

FIG. 7 is a bottom view of an exhalation module EVQ housing showing a new design.

The broken lines in the drawings illustrate portions of the exhalation module EVQ housing that form no part of the claimed design.
